FURNITURE SEAT

Max F. Wechsler and Mac Levine, Brooklyn, N. Y.,
assignors to Kay Manufacturing Corporation,
Brooklyn, N. Y., a corporation of New York

Application January 28, 1936, Serial No. 61,130

5 Claims. (Cl. 155—179)

This invention relates to spring seats for furniture such as chairs, sofas, couches and the like.

It has been customary heretofore to sustain a series of coil springs on a sheet or strips of burlap webbing secured to the bottom of the seat frame. Such burlap frequently stretches and becomes loose under the stresses of use with a resultant loss of supporting effect, and permits the bottom of the seat to sag and to become visible.

10 This invention contemplates the provision of a seat structure wherein the burlap spring-supporting sheet is stretched, reinforced and supported by a flat spring rigidly secured at its ends to the frame so that the sheet cannot sag and is maintained in its proper arched or raised position at all times.

15 This invention further contemplates the provision of a durable and efficient though economical seat structure, not likely to change its shape and lose its cushioning effect even under the stresses of prolonged use.

20 This invention further contemplates the provision of a seat structure employing an arched convoluted wire spring tending to resist deformation from its normal arched shape and well adapted for repairing and rendering efficient a sagging spring seat.

25 The various objects of the invention will be clear from the description which follows and 30 from the drawings, in which,

Fig. 1 is a top plan view of a typical seat with the upholstery covering thereof removed, which seat embodies one form of the present invention.

Fig. 2 is a vertical section of the same.

35 Fig. 3 is a perspective view of one of the sinuous springs used in the new seat structure for supporting the burlap sheet which holds the upright coil springs of the structure.

40 Fig. 4 is a perspective view of one form of the clip which is secured to the seat frame for rigidly holding the end of a sinuous spring.

Fig. 5 is a similar view of a modified form of the clip.

45 Fig. 6 is a vertical section of a modified form of the spring seat wherein the sinuous spring is arranged throughout its length underneath the burlap sheet.

Fig. 7 is a bottom plan view of the same.

50 Fig. 8 is a vertical section of the seat frame showing a modified form of the clip for holding the end of the sinuous spring in place.

Fig. 9 is a perspective view of the spring-holding clip shown in Fig. 8.

55 Fig. 10 is a view similar to Fig. 8 of another form of the spring-holding clip.

Fig. 11 is a perspective view of the same.

In the practical embodiment of the invention which I have shown by way of example, the numeral 10 designates the frame of the seat of the article of furniture, in which frame are arranged a series of rows of coil springs 11. Secured preferably about its entire periphery to the lowermost face of the frame 10 as by tacks or the like in the customary manner, is the sheet 12, preferably of burlap or other suitable textile material of 10 sufficient strength to support the springs 11, together with the weight of the person using the seat. Said sheet 12 is supported, reinforced, and stretched into its proper position by means of a series of sinuous arched wire springs 13, 14. 15

Said springs are similar to those disclosed in the patent to Karl Kaden, No. 2,002,399, dated May 21st, 1935, for Flat spring and method of making the same, and hence being well known, need not be further described in detail. Suffice 20 it to say that the spring is preferably made of metal wire and is provided with a plurality of continuous transverse convolutions of similar sizes and shapes and so arranged that the total thickness of the spring is not greater than the 25 thickness of the wire from which the spring is bent.

The spring may therefore be properly termed a "flat" spring since it is flat transversely. However, in its unstressed state, the spring is pre- 30 formed into an arcuate or arched shape so that the spring tends to retain its curl or arch, the ends of the spring tending to come together when the spring is partially flattened by the load put upon it. The sinuous spring is so attached to the 35 frame 10 as to partly straighten it while the spring still retains its arched shape. The ends of the spring therefore tend to come together or move toward each other owing to the tendency of the spring to assume its original and more 40 greatly arched shape. The sinuous springs may be secured to the frame in various ways but we prefer to arrange said springs so that they contact with the burlap sheet 12 only and do not directly or indirectly contact with the coil springs. 45 That is, said springs are arranged in between the coil springs and do not directly take the load put upon the coil springs.

Referring to that form of the invention shown in Figs. 1 and 2, the spring 13 is arranged with 50 the greater part of the length thereof underneath the sheet 12.

The end portions 15 and 16 of said spring are, however, arranged above the edge portion of the sheet. This is done by providing perforations as 55

17 and 18 in said sheet and threading the end portions 15 and 16 of the spring 13 through the respective perforations so that said end portions become disposed at the upper face of the sheet 5 12 while the remainder or intermediate part of the spring is disposed at the underside of said sheet. To secure the spring in its proper position, which is partly flattened from its normal highly arched state, as shown in Fig. 2, suitable 10 clips are secured to the inner face of the frame 10 at opposed points, the spring ends 23 held by a pair of said clips.

As shown in Fig. 4, the spring-holding clip may take the form of a plate 20, from which is struck 15 out or offset the spaced spring-holding portions 21 and 22. Said portions are offset a distance sufficient to permit the free end part 23 of the spring 13 to be inserted between said portions 21, 22 and the intermediate portion 24 of the clip.

20 The clip portions 21 and 22 are secured to the frame by suitable nails 25, screws, rivets or other fastening means as may be found desirable. Similarly, the portion 24 may be secured to the frame by an additional fastening member 26 25 driven into the frame. If desired, openings as 27, 28 may be made in the offset portions 21 and 22 for the reception of additional fastening means which enter the frame and which, being arranged in horizontal position above the spring end 23, 30 also serve to prevent possible lifting of said spring end out of the recess behind said offset portions.

As shown in Fig. 5, however, the clip may take the form of a plate 30 bent over on itself as at 31 35 to provide the opening 32 through which the spring end 23 may be passed.

The extreme end portion 33 of the spring may be turned downwardly or in any other direction to prevent possible transverse movement of said spring end in the opening, in whatever form of 40 clip is used to hold the spring.

It will be understood that the sinuous spring 14 is arranged relatively to the sheet 12 similarly to the spring 13, having its end portions similarly passed through perforations in the sheet 45 and secured to clips, which are in turn secured to the inner face of the frame.

Owing to the tendency of the springs 13 and 14 to return to their normal upwardly arched or convex shape, the intermediate portion of said 50 springs raises the sheet 12 above the level of the lower edge surface of the frame, said springs also resisting deformation to a sufficient extent to relieve the sheet 12 of a considerable portion of the pressure tending to tear said sheet adjacent 55 its securing means from the frame. Said springs 13 and 14 also impart to the upper surface of the seat its proper somewhat upwardly convex shape and to maintain said shape when the load on the seat is removed.

60 It will be noted that when pressure is put upon the seat, the convolutions of the sinuous springs are forced closer together to permit the over-all lengths of the sinuous springs to shorten somewhat under the stresses of use but without permitting the spring to become concave upwardly even under stress. The bottom of the seat structure is thereby always raised above the plane of the under edge of the seat frame 10.

70 The number of coil springs 11 may vary considerably. Said springs, however, are so arranged that the lowermost coil thereof rests directly on the flexible sheet 12, which in turn 75 stresses the sinuous springs 13 and 14 (Fig. 1) so that part of the pressure transmitted through said coil springs 11 may be put indirectly upon

the sinuous springs 13 and 14 if desired, and thence directly to the frame. It will be understood that the sheet 12 is so stretched and supported by said sinuous springs that the sheet is capable of supporting the coil springs 11 without danger of undue sagging or stretching, and that the desirable yielding or cushioning effect of the burlap sheet is nevertheless retained. 5

In that form of the invention shown in Figs. 6 and 7, the sinuous springs 35, 36 are secured 10 underneath the sheet 12 throughout the entire lengths thereof. The sheet 12 is nevertheless perforated by the clips 37 which retain the end portions 38, 39 of the sinuous spring in place. The clips 37, however, may take various forms. 15

As shown in Figs. 8 and 9, the clip 40 is provided with an upright plate portion bevelled to an edge 41 and provided with suitable openings 42, 43, 44 for the passage of fastening means such as the nails 45 into the frame 10. The plate portion of the clip 40 is secured to the inner face of the frame 10 in the same manner as the clips of Figs. 4 and 5 are secured. Bent from the lower edge of the pointed or plate portion of the clip 20 is a second portion 46 bent outwardly at right 25 angles to the remainder of the clip and provided with fastening holes 47, 48.

Preferably from the central portion of the part 46 is downwardly offset the spring-holding part 49 which is provided with a bend as 50 where it is 30 bent from the clip part 46.

The offset part 49 may also be provided, if desired, with a fastening hole 51. The clip is secured in the manner shown in Figs. 6 and 7 to the frame 10, the part 46 being in contact with 35 the upper surface of the edge part of the sheet 12 and the spring end 38 being preferably in contact with the part 50. If desired, a nail or other fastening means 52 may be driven through the perforation 51 into the frame to prevent inward 40 movement of the end 38 of the sinuous spring away from the bend 50. The point 41 is passed through the burlap sheet to make a perforation therein and to extend upwardly thereabove in order that the upstanding part of the clip may 45 be secured to the inner surface of the frame 10.

As shown in Figs. 10 and 11, the clip 60 may have an upright portion similar to the corresponding portion of the clip 40 but the remainder of the clip comprises the central part 61 bent as 50 at 62 from the upright part and indented to contact directly with the surface of the burlap. The nail or other fastening means 63 driven through the nail hole 64 of the part 61 aids in securing the clip adequately to the under edge of the frame 10. 55 On each side of the central portion 61 are the downwardly offset portions 65, 66, each provided with a perforation as 67, 68 for the reception of a fastening element driven therethrough and into the frame. The end 38 of the spring is 60 passed underneath the central portion 61 and above the side portions 65, 66 and is suitably held therebetween.

It will be understood that the clip is made of sheet material sufficiently soft to permit the extremities of the portions 65, 66 to bend around the spring end 38 when the fastening means are driven through the holes 67, 68 of said clip parts. Since the tendency of the spring is to contract, that is, to carry the ends 38, 39 toward each other, 70 the bend 62 at the extremity of the part 61 and the bends 69, 70 at the extremities of the respective parts 65, 66 prevent the spring end from coming out of the clip. The nails passed through the holes 67, 68 prevent the spring end from mov- 75

ing through the other end of the clip when the load is put upon the seat. The bending of the ends of the clip parts 65, 66 also aids in retaining the spring in place.

5 The above described form of our invention shown in Figs. 6 and 7 is particularly suitable for use in the repair and re-adjustment of spring seats wherein the burlap sheet has been unduly stretched and the structure thus shown may be 10 applied to any seat, whether of a continuous sheet of burlap or whether the strips of burlap are used to support the coil springs. This form of our construction is also suitable for new seats since the clips may be readily secured in place, both to the 15 inner face of the frame and to the lower edge thereof by merely passing the pointed ends 41 of said clips through the burlap and into contact with the inner face of the frame. The clips form adequate rigid supports for the ends of the sinous 20 springs and owing, as previously explained, to the tendency of said spring to return to its initial greatly convex position, form an efficient stretching means for the burlap to prevent any sagging thereof or to take up any sagging which has 25 already occurred.

It will thus be seen that by the present invention is provided a durable structure designed to maintain its proper shape throughout the life thereof and in which any sagging or undue 30 stretching of the fabric sheet, forming the bottom closure for the seat, is adequately taken up. It will further be seen that we have provided a structure well adapted for the repair of sagging seat structures and also well designed to meet 35 the severe requirements of practical use.

While we have shown and described a specific embodiment of our invention, it will be understood that we do not intend to limit ourselves thereto but desire to claim our invention as broadly 40 as may be permitted by the state of the prior art and the scope of the appended claims.

We claim:

1. In a spring seat provided with a hollow frame and with a burlap sheet secured around its 45 entire periphery to the lowermost edge surface of the frame and comprising a support for rows of coil springs, an L-shaped clip provided with a pair of legs arranged at right angles to each other, each of said legs being perforated, one of said legs 50 being upright and pointed at its upper end and passed through the burlap sheet into contact with an inner face of the frame and secured thereto, the other leg having the middle portion thereof from its outermost free end to the first-mentioned 55 leg arranged in vertical spaced relation above the remainder of said leg a distance substantially equal to the thickness of the spring hereinafter mentioned, said middle portion being secured to the lowermost edge surface of the frame with the 60 peripheral portion of said sheet therebetween, an arched sinuous spring extending completely across the frame and comprising the sole means for raising a selected area of the sheet, said spring being arranged underneath and in contact 65 with the sheet throughout the entire length thereof, a free end portion on the sinuous spring inserted underneath said middle portion and above the remainder of said other leg, said remainder being bent toward the burlap sheet to 70 substantially enclose said spring end, that part of said spring end projecting beyond said remainder being bent inwardly of the frame, and a second clip similar to said first-mentioned clip for the other end of the spring, said clips being 75 the sole supporting means for the spring.

2. In a spring seat provided with a hollow frame and with a fabric sheet secured to the frame, an arched sinuous spring terminating in a pair of free ends each bent at its extreme outermost part out of alignment with the adjacent 5 part thereof, said spring extending completely across the frame and underneath and in contact with the under face of said sheet and stretching said sheet upwardly, and means for rigidly securing said ends of the spring to the frame with the major portion of the spring in the interior of the frame comprising a pair of L-shaped clips each having a vertical leg pointed at its upper extremity passing through the sheet and secured to the inner face of and below the top of the frame and 10 having the other leg thereof secured to the under edge surface of the frame with the peripheral part of said sheet therebetween, said other leg having a pair of marginal offset portions extending below the mid-portion thereof and parallel 15 thereto and substantially coextensive in length therewith, said offset portion engaging and being bent about said free end of the spring, said spring comprising the sole means for raising a selected area of the sheet above the level which said sheet 20 would assume if unsupported by the spring.

3. In a spring seat having an upright frame open at its top and bottom, and having a burlap sheet secured around its entire periphery to the lowermost edge of the frame to close the bottom 30 of the frame, and also having a series of rows of upright coil springs resting on and supported solely by the burlap sheet, a plurality of flat spring members in frictional contact with the under face of the sheet and free and independent 35 of each other and of the coil springs, each of said spring members extending completely across the frame from one side to the opposite side thereof and being highest at its middle and each having a series of transversely extending flat 40 convolutions therein spaced apart a distance less than the width of the spring, each convolution having straight sides and rounded ends, said spring member being initially arched longitudinally in an arc of lesser radius than that assumed by the spring when secured in its operative position in the seat, and means for securing the ends of each of said arched spring members rigidly to the frame in arched position comprising a pair of L-shaped clip members, each 45 clip member having one leg fixedly secured to the inner face of the frame and below the top of the frame, each of said clip members having a second leg provided with a middle portion offset throughout the entire length of said second 50 leg from the remainder of said second leg and in parallel spaced relation to the adjacent parts of the second leg, said adjacent parts being bendable toward the frame, one of the end portions of the arched spring member being arranged to 55 pass across said offset and to project beyond the clip, said middle portion being secured to the bottom edge of the frame with the sheet therebetween, the projecting part of said end portion being bent laterally of the clip to prevent removal of said end portion from the clip, said one leg passing through the burlap sheet, said spring member being of sufficient strength to resist reduction of its convexity to a straight 60 line under all normal loads put on the seat, but yielding slightly under said loads to reduce its convexity and the consequent convexity of the sheet, the length of the arc of said spring member, when so yielding, being lessened, said 65 70 75

spring members comprising the sole means for arching the said sheet.

4. In a seat support for a seat having a substantially rectangular hollow frame completely closed at the bottom thereof by a fabric sheet secured thereto, said sheet being adapted to support rows of coil springs, a pre-arched sinuous spring having a tendency to curl into more accentuated arcuate forms, said spring extending 10 completely across the frame from one side thereof to the opposite side and being arranged underneath and in contact with the under face of the sheet for at least the greater part of the length of the spring, and means for fixedly and 15 rigidly securing the ends of the spring to the lower part of the frame at opposed points with the spring arranged in convex upward position in the lower part of the hollow interior of the frame and in a curve of greater radius than that 20 normally assumed by the spring if free at its ends, said spring securing and fixing means comprising a pair of L-shaped clips, one leg of each of said clips having a pair of spaced perforated coplanar offsets each having a width of about 25 one-third of the width of the clip and a length equal to that of said leg, said offsets being arranged in a plane in lateral parallel spaced relation to the plane of the remaining middle part of the leg to provide a spring-end receiving space

between the offsets and said middle part, said middle part being secured to the lower edge of the frame with the sheet therebetween, said offsets having free ends bendable toward the remainder of the clip and about the end of the 5 spring, each of said clips having a second pointed leg passing through the sheet and secured to the inner face of the frame.

5. An L-shaped clip member for use in holding the end of a sinuous spring rigidly to a frame 10 comprising a pair of substantially flat perpendicular legs, one of said legs being pointed at one end, the other leg having a pair of spaced perforated coplanar offsets arranged in a plane in lateral parallel spaced relation to the remainder of said other leg between said offsets and coextensive in length therewith, said remainder of said other leg terminating at said one leg and extending perpendicularly therefrom, said offsets providing a space between the 20 offsets and said remainder for the reception of the end of the sinuous spring and having free ends bendable toward the body portion and about said end of the spring, and a pair of right-angle bends at the juncture of said offsets with said 25 one leg, against which said spring end is drawn on the tendency of said spring to curl up.

MAX F. WECHSLER.
